ATTORNEY

UNITED STATES PATENT OFFICE

LEON S. BRACH, OF EAST ORANGE, NEW JERSEY, ASSIGNOR, BY MESNE ASSIGNMENTS,
TO GENERAL RAILWAY SIGNAL COMPANY

LIGHTNING ARRESTER

Application filed May 11, 1928. Serial No. 277,007.

This invention relates to a lightning arrester of the cartridge type in which there is provided a plurality of spark gaps for insuring a high degree of reliability and protection, and it is therefore the principal object of my invention to provide a lightning arrester which has a plurality of spark gaps so arranged as to insure reliability of action, and therefore a high degree of protection to the devices connected to the line with which the arrester is associated. Other objects will be apparent upon a study of the specification, taken in connection with the annexed drawing, in which:

18 Figure 1 is a plan view of the arrester with the casing broken away and showing certain of the parts in section.

Figure 2 is an end view of Figure 1.

Figure 3 is a diagrammatic illustration, 20 showing the association of the various spark gaps included in the construction of the arrester.

In the drawing, 1 is a tubular metal shell, having outside annular recesses 2 and 3. 25 These recesses are formed by depressing the metal inwardly so as to form abutments for the heads 4 of insulating material. Associated with the outer surface of each of the heads 4, is a metal washer 5, having its edges 8 turned inwardly to fit the beveled edges on the heads 4, and an insulator 6 for separating the washer 5 from a plate 7.

The elements 5, 6, and 7, constitute an arrester gap, there being provided openings 35 21 in the insulator 6, which is made of any suitable material such as mica. These arrester elements are held in position by a hollow stud 9 which passes through the head 4, and has its end 11 spun over a washer 40 10 so as to draw the head 12 of the stud into secure engagement with the plate 7. The head 4 is held in the end of the shell by crimping the end 15 of the shell 1 over the inwardly turned edge 8 of the washer 5. 45 This construction, therefore, connects in series the two spark gaps carried at opposite ends of the arrester.

The head 4 is provided with a recess which is not shown in the section taken, and the 50 end of the shell 1 is pushed inwardly, as in-

dicated at 22 (see Fig. 2) to enter the said recess, thereby preventing the head 4 from turning within the shell. It may be noted that the shell 1 is preferably provided with a small opening opposite the gap 18, so as to 55 permit inspection of the operation of this gap, if so desired. Since the shell 1 is broken away at this point, this opening does not show in the drawing.

Mounted within the shell 1, is a sealed 60 chamber 23 within which are positioned electrodes 16 and 17, forming a spark gap 18. Preferably, the electrodes 16 and 17 are made up of a plurality of twisted conductors of suitable material which are bound together 65 adjacent the spark gap 18 by binding plates 19 and 20. The chamber 23 may be of any suitable material such as glass, which is hermetically sealed, and in certain cases, a partial vacuum may be produced within the 70 chamber 23, or the chamber may be filled with some inert gas such as neon. In either case, the pressure within the chamber 23 is such as to permit the passing of an electrical current at a comparatively low voltage. 75

The electrodes 16 and 17 extend outside the chamber and are adapted to pass through the hollow studs 9, and are soldered as at 14, to the heads 12 of the studs, a recess 13 being provided to assist in making a good soldered 80 connection at this point. The thickness of the mica insulators or spacers 6, is chosen so that the voltage to jump this gap is somewhat higher than the voltage required to jump the gap 18 within the sealed chamber 85 23.

In ordinary operation of the arrester, the gap 18 will take the discharge, but in case of injury to chamber 23, which would impair the operation of the gap 18, then the 90 spark gaps at the ends of the arrester will take the discharge. In case of unusual lightning disturbances, all of the spark gaps may be brought into operation, even though the gaps at the ends of the arrester are connected 95 in series multiple with the gap 18.

From what has been said, it will be readily understood that the two series gaps connected in multiple with the main arrester gap within the sealed chamber, provide an auxiliary pro- 100

tection which is of considerable value, as these arresters are frequently installed on circuits where it is not safe to depend on one gap.

5. The arrester herein described, is adapted to be mounted between spring clips in the same manner as the ordinary design of fuses, and it is therefore easily and quickly replaced.

Having thus described my invention what 10 I claim is:

1. A lightning arrester having; a metal shell, heads of insulating material for closing each end of the shell, a hollow terminal stud carried by each of said heads, a metal 15 washer on the outer surface of each of said heads connected to said shell but spaced from said its associated stud, a metal contact plate associated with each of said studs, a spark gap disc of suitable insulating material located between said metal washer and the contact plate, a sealed chamber of insulating material located within said shell and electrodes carried by said chamber to form a spark gap inside the chamber and to extend through said 20 hollow studs for connection therewith.

2. A lightning arrester having; a metal shell, heads of insulating material for closing each end of the shell, a hollow terminal stud carried by each of said heads, a metal 30 washer on the outer surface of each of said heads connected to said shell but spaced from said its associated stud, a metal contact plate associated with each of said studs, a spark gap disc of suitable insulating material located between said metal washer and the contact plate, a sealed chamber located within said shell, electrodes carried by said chamber and extending within and without the same, those portions within the chamber 35 forming a spark gap while those portions without the chamber are adapted to pass through said hollow studs for connection thereto, said chamber having the gas therein in such condition that a comparatively low 40 voltage will jump the spark gap within the chamber.

3. A lightning arrester having; a metal shell, heads of insulating material for closing each end of the shell, a hollow terminal 50 stud carried by each of said heads, said heads having their outer edges beveled, a metal washer on the outer surface of each of said heads, but spaced from its associated stud said washers having crimped edges to fit the bevel edges of the heads, the ends of said shell being spun over the crimped edge of the washers to make contact therewith, a metal contact plate associated with each 55 of said studs, a spark gap disc of suitable insulating material located between said metal washer and the contact plate, a sealed chamber of insulating material located within said shell and electrodes carried by said 60 chamber to form a spark gap inside the chamber.

ber and to extend through said hollow studs for connection therewith.

4. A lightning arrester having; a metal shell with annular interior abutments near each end, heads of insulating material resting against said abutments and closing the ends of the shell, a hollow terminal stud carried by each of said heads, said heads having their outer edges beveled, a metal washer on the outer surface of each of said heads but spaced from its associated stud, said washers having crimped edges to fit the bevel edges of the heads, the ends of said shells being spun over the crimped edges of the washers to make contact therewith and to draw the heads against said abutments, means for preventing the heads and washers from turning in the shell, a metal contact plate associated with each of said studs, a spark gap disc of suitable insulating material located between said metal washer and the contact plate, a sealed chamber of insulating material located within said shell and electrodes carried by said chamber to form a spark gap inside the chamber and to extend through said hollow studs for connection therewith.

5. A lightning arrester having; a metal shell with annular interior abutments near each end, heads of insulating material held by the shell from turning and against said abutments, spark gap elements comprising conducting elements separated by a suitable perforated insulator carried by each of said heads, one conducting element of each gap held by the shell against said head, a hollow stud associated with a cooperating conducting element of each gap and acting to hold all of said spark gap elements on said heads a sealed chamber of insulating material located within said shell and electrodes carried by said chamber to form a spark gap inside the chamber and to extend through said hollow studs for connection therewith.

6. A lightning arrester having; a metal shell, heads of insulating material carried in each end of the shell, spark gap elements comprising conducting elements separated by a perforated insulator positioned on the outer surface of said heads one of said conducting elements being in contact with the shell a hollow stud passing through said gap elements and fastened to said heads for holding the said gap elements in place a sealed chamber of insulating material located within said shell and electrodes carried by said chamber to form a spark gap inside the chamber and to extend through said hollow studs for connection therewith.

7. A lightning arrester having plural spark gaps, one gap being within a sealed chamber, a protecting shell for the chamber and a spark gap positioned at each end of the shell, said shell connecting the corresponding conducting elements of the last

mentioned gaps while the co-operating elements of the last mentioned gaps are connected one each to the electrodes forming the sealed in gap.

- 5 8. A lightning arrester of the cartridge type comprising a metal shell, spark gap elements consisting of current conducting elements separated by a suitable perforated insulator mounted at the ends of said shell which 70
10 also serves to connect said spark gaps in series relation; a sealed chamber within said shell and having electrodes forming a spark gap within the chamber and extending outside the chamber for connection to the corresponding elements of said first mentioned gaps not connected by said shell.
- 15 9. A lightning arrester of the cartridge type having a metal shell, spark gap elements carried at each end of the shell and arranged 75
20 so as to be connected in series by said shell, a sealed chamber within the shell and having electrodes forming a spark gap within the chamber, said electrodes extending from the chamber and connected in parallel to the two 80
25 series of gaps.

10. A lightning arrester of the cartridge type including a sealed chamber having electrodes forming a spark gap therewithin, a conducting shell for carrying the chamber 85
30 and a set of air spark gap elements positioned at each end of the shell and connected in series by the shell but connected in parallel with the sealed in gap.

11. A lightning arrester of the cartridge type including a sealed chamber having electrodes forming a spark gap therewithin, a shell for carrying the chamber, insulators carried on each end of the shell, spark gap elements mounted on each of said insulators 90
35 40 and separated by perforated mica washers of a desired thickness, said shell serving to connect said spark gaps on said insulators in series and said gaps being in parallel with the sealed in gap.

- 45 12. A lightning arrester of the cartridge type including; a sealed chamber having electrodes forming a spark gap therewithin, a shell for carrying said sealed chamber, a set of air spark gap elements positioned at 95
50 each end of the shell and electrically connected in series, but connected in parallel with the sealed-in gap.

13. A lightning arrester of the cartridge type comprising a metal shell, spark gap elements consisting of current conducting elements separated by a suitable insulator at the ends of said shell which shell also serves to inter-connect said spark gaps in series relation; a sealed chamber within said shell, 100
55 electrodes forming a spark gap within the chamber and extending outside the chamber for connection to those corresponding elements of said first mentioned gaps which are not inter-connected by said shell.

- 60 65 14. A lightning arrester of the car-

tridge type including a sealed chamber having electrodes forming a sealed-in spark gap therewithin, a shell for carrying the chamber, insulators carried on each end of the shell, spark gap elements on each of said insulators and separated by mica washers of a desired thickness, said shell serving to inter-connect said spark gaps on said insulators in series with said spark gaps in parallel with the sealed-in spark gap.

In testimony whereof, I affix my signature.

LEON S. BRACH.
